(57) **CLAIM**

The ornamental design for a computer, as shown and described.

DESCRIPTION

FIG. 1 is a right, front, and top perspective view of a computer showing my design.

FIG. 2 is a front elevational view of the computer in FIG. 1 in the closed state.

FIG. 3 is a rear elevational view of the computer in FIG. 1 in the closed state.

FIG. 4 is a top plan view of the computer in FIG. 1 in the closed state.

FIG. 5 is a bottom plan view of the computer in FIG. 1 in the closed state.

FIG. 6 is a right-side elevational view of the computer in FIG. 1 in the closed state.

FIG. 7 is a left-side elevational view of the computer in FIG. 1 in the closed state.

FIG. 8 is a top plan view of the computer in FIGS. 1-7 in an opened state.

FIG. 9 is an enlarged view of an area “9” identified in FIG. 1.

FIG. 10 is an enlarged view of an area “10” identified in FIG. 1.

FIG. 11 is an enlarged view of an area “11” identified in FIG. 2.

FIG. 12 is an enlarged view of an area “12” identified in FIG. 5; and,

FIG. 13 is an enlarged view of an area “13” identified in FIG. 5.

The broken lines shown in the drawings are included for the purpose of illustrating portions of the computer that form no part of the claimed design. The dot-dashed broken lines in FIGS. 1, 2, 5, and 9-13 framing portions of the computer for enlargement purposes form no part of the claimed design.

1 Claim, 9 Drawing Sheets
